UNITED STATES PATENT OFFICE.

RALPH B. WILSON, OF CHICAGO, ILLINOIS.

LOOSE-LEAF LEDGER.

No. 847,628.

Specification of Letters Patent. Patented March 19, 1907.

Application filed October 18, 1906. Serial No. 339,428.

To all whom it may concern:

Be it known that I, RALPH B. WILSON, a citizen of the United States, and a resident of the city of Chicago, in the county of Cook and State of Illinois, have invented certain new and useful Improvements in Loose-Leaf Binders; and I do hereby declare that the following is a full, clear, and exact description of the same, reference being had to the accompanying drawings, and to the letters of reference marked thereon, which form a part of this specification.

This invention relates to improvements in loose-leaf ledgers, and more particularly to that class of loose-leaf ledgers set forth in my prior patent for ledger, issued May 26, 1903, No. 729,476.

While ledgers have heretofore been constructed having a collapsible closed back, it has been difficult to provide for closing the ends of the back, and many devices have been constructed for that purpose. These devices for closing the ends of the binder have proven expensive and sometimes have been objectionable, owing to the difficulty of securing the same rigidly in place though permitting the side sections free movement.

The object of this invention is to provide a ledger-back of the class described in which the central back plate carries the actuating means for the lateral clamping-plates and also is provided at its end with a casing integral therewith in which the transversely-turned ends of the clamping-plates telescope.

It is a further object of the invention to afford a construction wherein the ends of the clamping-plates are adapted to overlap each other within a casing rigidly secured upon the central back plate and having a rigid block secured therein on which said end members slide.

It is a further object of the invention to afford a back and end member of very strong and rigid yet extremely light construction adapted to permit large amplitude of adjustment of the clamping-plates to vary the quantity of leaves held therebetween and which is so constructed as to reduce the expense for construction to a minimum.

The invention consists in the matters hereinafter described, and more fully pointed out and defined in the appended claims.

In the drawings, Figure 1 is a view in elevation of the inner side of the binder. Fig. 2 is a section taken on line 2 2 of Fig. 1. Fig.

3 is a section taken on line 3 3 of Fig. 1. Fig. 4 is a section taken on line 4 4 of Fig. 1.

As shown in the drawings, A indicates a central back section comprising a plate stamped or bent to afford a convex outer and a concave inner surface and of a length equal to the length of the desired back of the binder and of a width approximately equal to the width thereof when in its collapsed or most restricted adjustment. Rigidly and, as shown, integrally secured on each end of said back section and extending inwardly and transversely at a right angle therewith and of somewhat less width are plates of the same thickness bent to afford the outer and the inner walls of a casing D D', closed at the top and open at each end. In the bottom of this casing and on the outer side, flush with the back, are relatively thick transverse bars a and a', respectively, having rounded edges and of a length equal to the width of said back section. These afford a finish for the ends of the back section and stiffen said section transversely. Said end bar a' is provided with a central notch, as shown in Figs. 1 and 2, and protruding therethrough is the angular end b of a shaft B, which, as shown, is journaled in suitable bearings b' b'', secured in longitudinal alinement in the middle of the back section. Said shaft is of a length approximately equal to the length of the back section and is provided at opposite ends beyond the bearings b' b'' with right and left screw-threads, respectively, as is usual with this class of binders. Secured on each of said ends, as shown, is a complementally-threaded nut B' and B'', wings from which project on opposite sides of the shaft and afford means for pivotally engaging thereto toggle-arms b³ and b⁴. Oppositely-disposed lateral clamping-plates C and C' are slidably secured upon said central back sections A, and each, as shown, comprises a plate of metal stamped to afford inwardly-turned ends d to d', which telescope in said casing D D', and an inwardly-turned relatively broad back flange c⁷ along the lower edge of each plate adjacent the central back section, and which fits closely and slides over the edges of the same. Said clamping-plates are engaged to said back section in part by means of said toggle-arms b³ and b⁴, which are pivotally engaged between said flanges and a suitable plate c⁸, parallel therewith, riveted to the binding-plate.

Rigidly secured in register with each other are a plurality of telescoping impaling-posts—as shown, three in number—each comprising tubular mutually telescoping members *c* to *c*⁵, inclusive, engaged on opposite clamping-plates and acting to engage the paper in place.

The operation is as follows: By inserting a suitable key through an aperture in said casing *D* the shaft may be rotated, moving the nuts oppositely on the shaft to increase or decrease the capacity of the binder dependent upon the direction of rotation. When rotated in either direction, the clamping-plates necessarily move simultaneously and to a like extent, and the overlapped ends thereof in the respective casing-guideways *D* and *D'* slide freely outwardly or inwardly to vary the capacity of the binder and are held at all times firmly engaged to the back section by said casing. The lower edge of the inturned ends *d* *d'* are cut away to pass over the end of the key or shaft; but it is quite obvious that the slot is not exposed to the ends of the casing to any appreciable extent even when the binder is expanded to its greatest extent, inasmuch as said casings are nearly as long as the width of the back section *A*. Furthermore, inasmuch as said casings are centrally located at the ends of said back plate and are integral therewith and extend nearly the entire width thereof they add greatly to the strength of the binder and serve to firmly engage the clamping-plates thereof and obviate any tendency for the back sections to spring away from the clamping-plates.

The bearings for the screw-shaft may of course be constructed in any suitable manner. As shown, however, the shaft at the inner end of each screw-threaded portion is slightly reduced in diameter and is supported by bearing-blocks *b*⁶ *b*⁶, and straps of metal *b*' *b*² are bent to the desired shape to engage around the same and the shaft, and the ends thereof are carried downwardly and riveted to the back plate, as shown in Figs. 1 and 3.

Obviously while I have shown my invention as provided with three sets of telescoping impaling-posts the binder is capable of considerable variation in this respect, and in certain forms of binders the impaling-posts may be omitted, if desired, and the clamping-plates permitted to frictionally engage the margins of the paper, and various details of construction may be varied without departing from the principle of this invention.

I claim as my invention—

1. A loose-leaf binder embracing a centrally-curved back section, lateral clamping-plates slidably engaged thereon, impaling-posts secured thereto and slidably therewith, inturned overlapping ends on said clamping-plates and a central transverse elongated casing engaged on each end of said back plate

and affording a housing for said overlapped ends of the clamping-plates, said housings having an enlargement at the lower ends, a strengthening-bar extending through the housing, and means for actuating said clamping-plates.

2. A ledger-binder of the class described embracing a curved back plate of sheet metal, a transverse reinforcing-bar rigidly engaged on each end thereof, a central elongated transverse casing, on each end of the back plate and integral therewith and adjacent the reinforcing-bar, oppositely-slidable clamping-plates laterally engaged on the back plate, inturned ends on said clamping-plates adapted to project approximately through and to overlap each other in said casing or housing, an actuating-shaft journaled longitudinally and centrally of said back plate, an angular end thereon projecting through one of said housings and the overlapped ends of said clamping-plates and mechanism operated by said shaft to shift said clamping-plates.

3. In a device of the class described a transversely-curved sheet-metal back plate having a length approximately equal to the length of the binder and in width approximately equal to the thickness of the binder in its most contracted form, a right and left end threaded shaft journaled longitudinally at the middle of said back plate, and reduced in diameter at equal distances from its ends, bearing-blocks adapted to support the same at the reduced portion, straps engaged around the shaft and bearing-blocks firmly securing the shafts from longitudinal movement, clamping-plates shaped to afford an inturned flange adjacent the back plate, inturned ends on the clamping-plates, interfitting impaling-posts carried on the clamping-plates, a traveling carriage on each end of said shaft, toggle-bars pivotally connected therewith and with the clamping-plates, transverse reinforcing-bars one at each end of the central back section, an elongated transverse housing or casing integral with the back plate and projecting into the binder and in which said ends of the binding-plate overlap.

4. In a ledger-binder a sheet-metal back section concave on the inner and convex on the outer side, rigidly-secured transverse reinforcing-bars one at each end of said section, and integral transverse housings at the ends of the back section and in which the reinforcing-bars are rigidly secured.

5. A pressed-metal back plate of the class described having transverse inwardly-directed housings integral therewith at each end, said housing provided with an enlargement at one end thereof and transverse bracing-bars engaged in said enlargements.

6. A pressed-metal back plate of the class described having at each end an integral

transverse inwardly-directed casing having parallel walls, and a reinforcing-bar flush with the back on the outer side and permanently secured between said sides.

5 7. In a ledger-binder, a pressed-metal back plate having an integral housing at each end and the outer wall of said housing turned outwardly to form an enlargement and a bar closely fitting said enlarged portion of the 10 housing to strengthen the ends of said binder.

8. A ledger-binder of the class described comprising a back plate concave on its inner side and convex on its outer side, a housing at each end of said back-section and a strengthening-bar rigidly inclosed within the walls of 15 said housing.

9. In a binder of the class described the combination with a back plate of side plates having inturned ends, a housing rigidly engaged at each end of the binder of uniform 20 width approximately the height of the end plates and affording an enlarged passage below the same and a strengthening-bar engaged therein and firmly riveted thereto.

10. The combination with a pressed-metal 25 back plate of clamping-plates movable thereover, a housing at each end of the back and a strengthening-bar extending through each housing and providing a finish for each end of the back.

11. In a binder of the class described the combination with a back plate of clamping-plates movable thereon, a strengthening-block riveted to each housing and affording a finish for each end of the binder, a central 30 shaft journaled on the back plate and having one end projecting through one of said housings and inturned ends on said clamping-plates extending into the housing and those on one side notched to clear the end of 40 said shaft.

In testimony whereof I have hereunto subscribed my name in the presence of two subscribing witnesses.

RALPH B. WILSON.
